UNITED STATES PATENT OFFICE.

ADOLPHE COLLIN, OF OUGREE, AND DIEUDONNÉ JEUNEHOMME, OF JEMEPPÉ,
BELGIUM.

POURING LADLE.

Application filed January 6, 1922. Serial No. 527,455.

To all whom it may concern:

Be it known that we, ADOLPHE COLLIN and DIEUDONNÉ JEUNEHOMME, subjects of the King of Belgium, residing, respectively, 5 in Ougree, rue Champs du Mont, and in Jemeppe sur Meuse, rue de la Station, Belgium, have invented certain new and useful Improvements in Pouring Ladles; and we hereby declare the following to be a full, 10 clear, and exact description of the invention, reference being made to the accompanying drawings, which form a part of this specification.

The present invention has for its object 15 to obviate the disadvantages resulting from the actual means of tilting, in which the axis of the single worm wheel or the like, controlling the tilting, is horizontal. To this end, the wheels or worms run in a protecting 20 housing or box secured only to a supporting arm of the ladle and on which is vertically guided the end of the trunnion of the ladle, or a part carried thereon, so that any movement of the geared transmission mechanism 25 and any torsional effort are prevented. Moreover in order to prevent the twisting of the wheels causing the seizing of the trunnions on their bearings, the toothed wheel mounted on the trunnion is actuated either 30 by a worm or the like, the axis of which is vertical, either by several worms or the like, the axis of which are parallel and symmetrically adapted to the wheel.

Another object of the invention is the provision of a complete lubrication of the train 35 of gears controlling the wheel keyed upon the end of the trunnion supporting the ladle. For this purpose, the axes of these gears are inclined downwards and the hub of the 40 wheel is provided with passages in which the lubricating oil is compelled to penetrate.

Another object of the invention consists 45 in the production of a renewable air-interval between the ladle and its ring in order to reduce the getting hot of the supporting trunnion and to suppress any cause of expansion from the tilting mechanism.

In the accompanying drawings, Fig. 1 shows a ladle in section through the axis of 50 suspension, on line A—B of Fig. 3; Fig. 2 is a detail of the end of the trunnion in section upon line C—D of Fig. 3; Fig. 3 is a section upon line E—F of Fig. 1; Fig. 4 is an external view of the protecting box or 55 housing; Figs. 5 and 6 are two construc-

tional modifications of the attachment of the protecting box or housing; Figs. 7 to 11 show different positions of the controlling gear of the wheel; Fig. 12 is a section upon line G—H of Fig. 1.

Upon the trunnion 1 secured to the ring 2 is keyed a worm wheel 3 operated by an endless screw or worm 4. The shaft 5 of this worm carries a bevel wheel 6 receiving motion from another bevel wheel 7 mounted upon a shaft 8 operated from the exterior by a lever, a hand wheel or the like, which engages, for example, with the squared end 9 of the shaft 8.

The trunnion 1 rests upon a series of 70 rollers or rolls 10 enclosed in a race-way such as 11 secured to the arm 12 of the ladle, the said arm supporting by means of bolts the protecting box or housing 13 of the geared transmission mechanism. The end of the 75 trunnion 1 carries by means of rollers 14 a race 15 similar to the race 11. As shown in Figs. 2 and 4, this race 15 is provided with arms 16 guided laterally and retained by parts 17 forming slides and secured to the 80 housing. In this way, the housing is made independent from the ladle, so that the reactions of the trunnion's end have no influence on the housing and consequently on the 85 supporting arm, which suffers no torsional effort.

The hub of the wheel 3 is formed with a series of holes 18, which as they come in front of corresponding holes 19 in the race 11, ensure the circulation of oil carried by 90 the arms 20 of the wheel 3 dipping into this oil.

As shown in Fig. 1, the leverage producing the zone *a* of torsion is very short, the effect is consequently minimized; this 95 advantage is of greatest importance, because it thus reduces considerably a frequent cause of unsatisfactory operation of devices of this kind.

The supporting arm 12 may be of any 100 appropriate form, either as shown in Figs. 1 and 5, two right flat bars enclosing the race 11, or as shown in Fig. 6, two bars incurved towards the middle of their height in order to embrace the housing 13. On 105 these bars is bolted an incurved plate 21, forming slide for the race in the Fig. 5, or secured to one of the bars 12 for supporting the race 11, as shown in Fig. 6.

In the construction shown in Figs. 1 to 110

6, the axis of the endless screw or worm 4 is horizontal; as the plane of reactions of this worm is perpendicular to the vertical plane of the suspension arm 12, a binding 5 of the trunnions on their bearings may be caused. In order to prevent this disadvantage, the one or the other of the constructions represented in Figs. 8 to 11 may be used.

10 As shown in Fig. 7, the worm is vertical, whereby the reaction of this worm is no more in the horizontal direction, but in the direction of the vertical axis, consequently one cause of twisting is avoided, as the reaction 15 of the worm is in a vertical plane parallel to the vertical plane of the supporting arm. This vertical arrangement of the worm 4 is theoretically the best, but in order to obtain an ample lubrication and 20 to allow the worm to dip into an oil-bath, a suitable inclination downwards is given to the worm 4, so that its axis and that of the arm meet each other under the trunnion 1, as shown in Fig. 8.

25 For the purpose of obtaining a complete equilibrium of the system, and avoiding any eccentricity of the worm and any torsion of the arms, it is advantageous to replace the single worm of the precedent construction 30 by two or more worms symmetrically adapted upon the wheel mounted upon the trunnion and parallel two by two, so as shown in Figs. 9 and 10, where respectively vertical and horizontal worms 4 and 4' actuate the same 35 wheel 3. The worms 4 and 4' are thus opposed one to the other in all positions in respect to the axis of the supporting arm. The torsional forces are thus combined and balanced.

40 The worms 4 and 4' are operated by a single transmission, spur gears or bevel gears, worm wheels or the like. For example in Fig. 10, on the shafts of the worms 4 and 4' are secured spur gears 22 engaging 45 with a toothed gearing 23 mounted upon the shaft 24 actuated by a hand wheel.

45 But, as in the case of the single vertical worm of Fig. 7, the worms 4 and 4' are difficult to be well lubricated, therefore the 50 construction of Fig. 11 is more practical, in which the two worms 4 and 4' engaging with the wheel 3 are inclined downwards, so that their axes form an angle of about 90°. The shafts of these worms carry spiral 55 gears 25 engaging with a spiral gear 26 keyed upon a shaft 27 controlled directly or indirectly by a hand wheel. The whole mechanism is enclosed in a housing 28 secured solely to the arm 12 and dipping into an oil-bath. Furthermore a second support 60 is not necessary for the trunnions carrying the worms 4 and 4'.

65 In this modification a zone of torsion exists at the ends 29 of the worms, while the ends 30 are balanced. In order to ob-

viate this fault, the combination of the two inclined worms is used with the sliding race 15, as represented in Figs. 1 to 6.

The ring 2 (Figs. 1 and 12) is not directly secured against the ladle, but is in contact with the latter by means of a series of wedges 32, or the like, riveted or bolted as in 31, so that an interval 33 exists between the ladle and the ring 2.

In this interval 33, as indicated by the 75 arrows 34, an air-current is obtained, maintaining the ring 2 and consequently its trunnions 1 at a low degree of temperature, and so preventing abnormal heating of these organs. The ascensional air-current indicated by the arrows 34 contact the ring 2 and thus favours its cooling, inasmuch as the conductibility is minimized and the 80 radiation much attenuated.

Any risk of binding because of the raising 85 of the temperature being avoided, the coefficient of resistance of the organs may be raised. It will be seen that during the tilting of the filled ladle some cast-iron flowing away along the ladle, will not remain 90 upon the ring, which was thus submitted to a notable rising of temperature.

It will be evident that various modifications may be made in the construction and arrangement of the various parts without 95 departing from the spirit of the invention, or exceeding the scope of the appended claims.

Having fully described our invention, what we desire to claim and secure by Letters Patent is—

1. In a pouring ladle, the combination of, a supporting arm for the ladle; a ring secured to the ladle; a horizontally extending trunnion secured to said ring; tilting mechanism cooperating with said trunnion; a housing for said mechanism, the mechanism being controlled from the exterior of the housing; roller bearings for the trunnion; and race-ways for the roller bearings on either 105 side of said housing, the race-ways being movable vertically on the housing.

2. In a pouring ladle, the combination of, a supporting arm for the ladle; a ring secured to the ladle; a horizontally extending 115 trunnion secured to said ring; tilting mechanism cooperating with said trunnion; a housing for said mechanism, the mechanism being controlled from the exterior of the housing; roller-bearings for the trunnion; race-ways for the roller bearings on either side of said housing, the race-ways being movable 120 vertically on the housing; and means for guiding the race-ways laterally on the housing.

3. In a pouring ladle, the combination of, a pair of supporting arms for the ladle; rings secured to the ends of the ladle; horizontally extending trunnions secured to the 130 rings; tilting mechanism appurtenant to one

of said trunnions; a housing for said mechanism; means for actuating said mechanism operable from the exterior of the housing; roller-bearings for one of said trunnions; a 5 race-way for said roller-bearings; roller-bearings for the other of said trunnions; race-ways for the last mentioned roller-bearings arranged on either side of said housing; said race-ways being movable vertically on 10 the housing; and means for guiding said race-ways laterally on the housing.

4. In a pouring ladle, the combination of, a pair of supporting arms for the ladle; rings secured to the ends of the ladle; means 15 for circulation of air between said rings and the ends of the ladle; horizontally extending trunnions secured to the rings; tilting mechanism appurtenant to one of said trunnions; a housing for said mechanism; 20 means for actuating said mechanism operable from the exterior of the housing; roller-bearings for one of said trunnions; a race-way for said roller-bearings; roller-bearings for the other of said trunnions; race-ways for 25 the last mentioned roller-bearings arranged on either side of said housing, said race-ways being movable vertically on the housing; and means for guiding said race-ways laterally on the housing.

30 5. In a pouring ladle, the combination of, a pair of supporting arms for the ladle; rings secured to the ends of the ladle; horizontally extending trunnions secured to said rings; tilting mechanism appurtenant to one of said 35 trunnions and comprising a worm wheel and worm means for driving the worm wheel; roller-bearings for one of said trunnions, a race-way for said roller bearings; roller bearings for the other of said trunnions; race-ways for the last mentioned roller-bearings, said race-ways being movable vertically on 40 the housing; means for guiding said race-ways laterally on the housing; and means appurtenant to the worm wheel cooperating 45 with means appurtenant to one of the race-ways for distributing oil from the worm wheel.

6. In combination, a tiltable ladle; rings 50 on the ends of the ladle; and means for providing circulation of air between said rings and the ends of the ladle.

55 7. In a pouring ladle, the combination of, a ladle; a trunnion for the ladle; roller-bearings for the trunnion; race-ways for the roller-bearings; mechanism for tilting the ladle and comprising a worm wheel and worm means for driving the worm wheel; and means appurtenant to the worm wheel cooperating with means appurtenant to one 60 of said race-ways for distributing oil from the worm wheel.

8. In combination, a ladle; trunnions mounted on the ladle; supporting bearings receiving said trunnions; an adjustable bear-

ing on one of the trunnions; and operating 65 means on the same trunnion between the adjustable and supporting bearings.

9. In combination, a ladle; trunnions mounted on the ladle; a support having bearings receiving said trunnions; a vertically adjustable bearing receiving one of 70 said trunnions; a worm wheel fast between the adjustable bearing and the bearing of the same trunnion; and a worm engaging said wheel.

75 10. In combination, a ladle; trunnions mounted on the ladle; a support comprising arms having bearings receiving said trunnions; a worm wheel fast on one of the trunnions near the outer face of the adjacent arm; a housing fixed on said adjacent arm and enclosing the wheel; a vertically adjustable bearing at the outer face of the housing receiving said trunnion; a worm mounted in said housing and engaging said wheel; and means exterior to the housing for operating the worm.

80 11. In combination, a ladle; trunnions mounted on the ladle; a support comprising arms having bearings receiving said trunnions; a worm wheel fast on one of the trunnions near the outer face of the adjacent arm, and having its hub provided with arms and bores radial at one end and leading to the adjacent fixed bearing at the other end; 85 a housing fixed on said adjacent arm and enclosing the wheel; a worm mounted in said housing and engaging said wheel; and means exterior to the housing for operating the worm.

90 12. In combination, a ladle; trunnions mounted on the ladle; a support comprising arms having bearings receiving said trunnions; a worm wheel fast on one of the trunnions near the outer face of the adjacent arm; a housing fixed on said adjacent arm and enclosing the wheel; a non-horizontal worm mounted in said housing and engaging said wheel; and means exterior to the housing for operating the worm.

95 13. In combination, a ladle; trunnions mounted on the ladle; a support comprising arms having bearings receiving said trunnions; a worm wheel fast on one of the trunnions near the outer face of the adjacent arm; a housing fixed on said adjacent arm and enclosing the wheel; a pair of symmetrically disposed non-horizontal worms mounted in said housing and engaging said wheel; and means exterior to the housing 105 for operating the worms.

110 In testimony whereof we sign in the presence of two witnesses.
